P. V. LINDMARK

BRUSH HOLDER

Filed July 17, 1923

UNITED STATES PATENT OFFICE.

PRIMUS V. LINDMARK, OF KANSAS CITY, MISSOURI.

BRUSH HOLDER.

Application filed July 17, 1923. Serial No. 652,137.

To all whom it may concern:

Be it known that I, PRIMUS V. LINDMARK, a citizen of the United States, residing at Kansas City, in the county of Jackson and 5 State of Missouri, have invented certain new and useful Improvements in Brush Holders, of which the following is a specification.

This invention relates to improvements in brush holders.

10 The present invention is particularly adapted to serve as a holder for supporting paint brushes in a softening liquid, such as linseed oil or the like.

15 Among the objects of the invention is to provide a brush holder of the above character which is inexpensive to manufacture; which may be adjusted to support a brush in a body of liquid so that the bristles of said brush will not engage with the bottom 20 of the container for said liquid; which can be arranged or adjusted to accommodate brushes of different sizes or widths, and which is adapted to hold the free end of the bristles of the brush supported thereby 25 in a compact manner.

It is also an important object of the invention that the brush holder be adapted to be adjusted or arranged so that the same will support two or more brushes if so desired.

30 Other objects, and objects relating to details of construction, combination and arrangement of parts will hereinafter appear in the detailed description to follow.

The invention is illustrated by way of example in the accompanying drawings, in which:

Figure 1 is a vertical sectional view taken through a pail with the softening liquid therein and showing a holder of the present 40 invention utilized for supporting a brush within the liquid in said pail,

Figure 2 is a vertical sectional view of the brush holder,

Figure 3 is a perspective view of the device showing one section in dotted lines and particularly illustrating the supplementary and adjustable side wall utilized in connection with the holder,

Figure 4 is a transverse sectional view taken substantially on the line 4-4 of Figure 3 when looking in the direction of the arrows,

Figure 5 is a detailed perspective view of the supplementary side wall,

55 Figure 6 is a transverse sectional view of the brush holder when the sections thereof

are arranged to support two or more brushes therebetween, and

Figure 7 is a fragmentary perspective view illustrating the sections when arranged as in Figure 6.

Referring to the drawings more particularly, the holder preferably comprises the two sections 10 and 11. The section 10 may comprise an elongated plate member 12 which tapers toward its lower end and each longitudinal edge thereof turned or curved inwardly to provide the two side walls 13. Each side wall 13 is substantially U-shaped in cross sectional contour, as shown, and 70 terminates at its free end in a bead 14 which is preferably formed in each instance to slidingly accommodate a rod 15. The rods 15 constitutes legs which are preferably integrally connected at their lower ends by a 75 cross portion 16. Also this section of the holder has pivoted to its upper end a bail 17.

The section 11 comprises an elongated plate member 18 which also has each of its longitudinal edge portions turned or curved 80 inwardly to provide the two side walls 19, each of which is substantially U-shaped in cross sectional contour. This section is adapted to slide within the section 10, as illustrated to advantage in the drawing. 85 The section 11 also is provided at its upper end with a bail 20.

The section 11 is provided with two rows of openings 21 and 22. The rows are arranged one above the other as illustrated in 90 the drawing, and each opening of both rows has its one end terminating in an enlargement 23. What may be termed a supplementary side wall is provided. This wall is generally designated by the reference number 24, and comprises a plate substantially 95 U-shaped as shown and having its upper end terminating in a tang or extension 25. One longitudinal edge of the plate is turned upon itself, as at 26, and this turned portion 100 carries a pair of pins 28 and 29. Each pin has its free end turned downwardly, as shown. Either of the openings 22 is adapted to receive the pins 29 and the same is true with respect to the openings 21 and pin 28. 105

By engaging the pins 28 and 29 of the member 24 in aligned openings 21 and 22, respectively, the same can be positioned upon the section 10 of the holder, as illustrated in Figure 3. The member 24 can be adjustably 110 moved in either direction upon the section 10 as is entirely apparent.

As shown in Figure 1, 30 indicates generally a container which is partially filled with a softening liquid 31. The holder is shown positioned within the container 30 and supports a brush 32.

In positioning a brush 32 in the holder the same can be arranged so that it is disposed between the side walls of the section 11. These side walls taper toward the lower end of the holder, and in this way the bristles of the brush are held in a compact manner and thus tend to prevent spreading of these bristles when the brush is used for painting or the like. Also with the brush holder positioned as in Figure 1, for supporting a brush, the legs 15 can be adjusted so that the free ends of the bristles of said brush do not engage with the bottom of the pail.

As shown in Figure 1, the brush 32 is of such a width that the same will nicely fit within the side walls of the section 11. Should the brush be of less width than the distance between the side walls of the section 11, then the supplementary side wall 24 may be utilized for clamping the brush within the holder. The supplementary side wall may be positioned in an obvious manner and the same may be applied either after or before the brush has been positioned within the holder.

Referring to Figure 6, it will be seen that the sections 10 and 11 of the brush holder are differently arranged than shown in Figure 1. In this instance, the free edges of side walls 19 of section 11 are brought to engage with the beads 14 of the section 10. This may be done by sliding the section 11 upwardly upon the section 10, and as shown in Figures 6 and 7, the two sections so coupled or connected will provide a receptacle or holder which is adapted to receive two or more brushes. The legs 15 may be adjusted in this instance as well as in the arrangement shown in Figures 1 to 5, inclusive, and also if desired the supplementary side wall 24 may be utilized.

While I have shown and described the preferred form of my invention, I wish it to be understood that I am aware of the fact that the construction, combination and arrangement of parts may be changed by those skilled in the art without departing from the spirit of the invention, as indicated by the appended claims.

I claim:

1. A device of the character described comprising a pair of sections, each consisting of a plate having a pair of substantial-

ly U-shaped side edge portions, said sections being adapted to be arranged selectively with one of said sections in interfitting relation to the other section to provide a single brush holder or with the corresponding side walls of the two sections engaged with each other at their free edges to hold the sections in juxtaposed relation and to thus provide a double brush holder.

2. A device of the character described comprising a pair of sections, each consisting of a plate having substantially U-shaped side edge portions constituting a pair of side walls for the section, the side walls of one section having beads extending along the free edges thereof and the other section being adapted to be disposed selectively in interfitting relation to said one section or with the side walls thereof in engagement at its side edges with the beads of the first section to hold said sections in juxtaposed confronting relation in respect to each other.

3. A brush holder comprising a section consisting of a plate member having the side edge portions thereof, bent substantially into U-shape to provide a pair of side walls, and a substantially U-shaped supplementary wall supported on the plate member and adapted to cooperate with one of said first named side walls, said supplementary wall being bodily movable along said plate to vary the distance between said one first named side wall and the supplementary wall, said plate member and said supplementary wall having cooperative means for releasably holding said supplementary wall rigid with the plate member in various adjusted positions along the latter.

4. A brush holder comprising a section consisting of a plate member having the side edge portions thereof bent substantially into U-shape to provide a pair of side walls, and a substantially U-shaped supplementary wall supported on the plate member and adapted to cooperate with one of said first named side walls, said plate member having vertically spaced rows of spaced apart openings extending transversely thereof and said supplementary wall having laterally extending pins corresponding in number and arrangement with said rows of openings and each being engageable selectively with the openings of a row, whereby the supplementary wall may be releasably held rigid with the plate member in various adjusted positions along the latter.

PRIMUS V. LINDMARK.
